CHAD DISPOSAL MEANS

Clayton H. Clark, Mundelein, Ill., and Carl P. Anderson, Homer, N.Y., assignors to SCM Corporation, New York, N.Y., a corporation of New York
 Application May 14, 1964, Ser. No. 367,410, now Patent No. 3,274,338, which is a division of application Ser. No. 157,540, Dec. 6, 1961, now Patent No. 3,205,305. Divided and this application Apr. 28, 1966, Ser. No. 545,940

5 Claims. (Cl. 178—17)

This application is a division of co-pending application Ser. No. 367,410, filed May 14, 1964, now Patent No. 3,274,338, which is a division of application Ser. No. 157,540, filed Dec. 6, 1961, now Patent No. 3,205,305. The invention pertains to an improvement in the means for carrying chad away from the perforating station of punched record coded recording means.

In punched card and tape perforators the chad or material which is punched from the records to make the coded perforations is normally directed away from the perforating station by means of a duct which has a chad receiving hood at the exit of the dies. When the chad is punched from the record it is pushed up into the hood over the die and flows through the disposal duct to a container located away from the mechanism, but in some instances the duct becomes clogged and that is particularly true in high speed perforators. The purpose of this invention is to overcome the disadvantages of blocking of the chad duct.

Accordingly a primary object of the present invention resides in the provision in a perforator of a chad exit cover and deflecting or disposal duct provided on its inner surface with a dry lubricant to obtain non-clogging smooth outflow of chad from the dies at ultra-high speeds of operation. In conjunction herewith it is a further object to provide a coating of molybdenum disulfide as the dry lubricant.

Further novel features and other objects of this invention will become apparent from the following detailed description, discussion and the appended claims taken in conjunction with the accompanying drawings showing a preferred structure and embodiment, in which:

FIGURE 1 is a perspective detail view showing the compact arrangement of multiple punches and operating components of a perforator machine utilizing the chad disposal means of the present invention; and

FIGURE 2 is a partially sectioned elevation view of a portion of the punches of the mechanism of FIGURE 1 and illustrates the chad pick-up head in section at the die exit.

The details of the perforating machine punch and selecting unit 500 shown in FIGURE 1 are fully disclosed and described in both of the aforesaid applications and will not be described in detail herein.

The record medium to be perforated can be any thin sheet medium such as card, fanfold stock or tape 510 as illustrated.

In the exemplary perforator a group of punches 598, nine including the feed hole punch are reciprocally mounted in alignment in a punch guide 592 rigidly secured to the machine frame. Above the punch guide is the tape guide and die assembly 594, the lower guide plate 596 of which is coplanar with the flat table top of machine 500 forming the record medium track, and the chad removal tube 522 abuts over the chad exit portion of upper die plate 597 forming the chad exit head or hood 524.

2

Primary feed and back spacing of the record medium, whether it be tape, cards or fanfold, is accomplished by means of an indexed rotatable sprocket feed roller 650 located below the record media track and positioned just after the punching station. A preliminary indexed feed wheel 651 is also used in the card and fanfold modes of operation. A plurality of feed pins 652, secured in the periphery of feed roller 650 engage properly spaced feed holes in the record medium so that stepped rotation of roller 650 causes a stepped feed movement of the record medium.

During operation of the machine a chad box (not shown) inside the main machine housing will, in time, become filled and when this occurs, a signal of some kind will be given to the operator. The chad box of course should then be emptied.

A dry form of lubricant, specifically molybdenum disulfide 600, applied by spraying or dipping, on the interior of the inlet of chad tube 522 above die plate 597 will assure freedom of passage of the chad through the tube. This dry lubricant prevents blocking of the chad tube which results in malfunctions of the equipment when the chad is generated at ultra-high speeds.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by Letters Patent is:

1. In combination: a recording device having recording mechanism comprising a plurality of code punch and die sets, and means to collect and direct chad from said punch and die sets away from said recording mechanism comprising a die exit hood, at least the interior surface of which is a dry lubricant.

2. In a recording device as defined in claim 1, said dry lubricant including molybdenum disulfide.

3. In combination: a punch and die device for perforating a record medium, said device including movable punch means and associated die means having a die exit through which chad is discharged, chad disposal means for conducting chad away from said die exit, said chad disposal means including a hood having an inlet communicating with and enveloping said die exit, and a coating of dry lubricant on the interior of said hood at least adjacent its inlet.

4. The combination as defined in claim 3, wherein said dry lubricant includes molybdenum disulfide.

5. The combination as defined in claim 3, wherein said hood inlet is the sole inlet to said hood and said punch means constitutes the sole means for urging chad through said hood.
